UNITED STATES PATENT OFFICE

SALVATORE LAFRANCA, OF NEW YORK, N. Y.

PIPE

Application filed December 26, 1930. Serial No. 504,895.

This invention relates to new and useful desired construction, and suitably secured improvements in smoking pipes.

It is one of the objects of the invention to provide a smoking pipe which is so constructed that the saliva from the mouth of the smoker cannot enter the bowl or tobacco receptacle of the pipe.

It is a further object of the invention so to construct a smoking pipe that the smoke in its passage from the bowl of the pipe to the discharge end of the stem thereof will be cooled.

It is a still further object of the invention, so to construct a smoking pipe that the same may be easily cleaned.

A still further object of the invention resides in the provision of means which is removably carried by the pipe for preventing the entrance of saliva to the bowl of the pipe.

With the above and other objects in view, reference is had to the accompanying drawing, in which,

Figure 1 is a longitudinal sectional view of a pipe constructed in accordance with the present invention,

Figure 2 is a top plan view thereof showing the bowl in section and taken on the line 2—2 of Figure 1,

Figure 3 is a plan view of the removable portion of the stem.

Figure 4 is an enlarged detail sectional view taken on the line 4—4 of Figure 1.

Figure 5 is a detail sectional view taken on the line 5—5 of Figure 1.

Figure 6 is a bottom perspective view of the pipe bowl,

Figure 7 is a detail sectional view of a pipe bowl constructed in accordance with the present invention and showing the manner in which certain portions of the pipe bowl are formed,

Figure 8 is a detail bottom plan view of one of the elements which go to make up the pipe, and

Figure 9 is a perspective view of an implement employed for removing the plug.

Referring particularly to the drawing, the reference numeral 10 designates the pipe bowl, 11 designates the stem, and 12 designates the bit thereof. The bit may be of any

desired construction, and suitably secured therein as at 13, there is a tube 14 which extends from the forward end of the bit and which has an enlarged portion 15 which is screw threaded as designated at 16. This tube 15 may be anchored within the bit 12 by knurling the same as indicated at 17 in Figure 3, and the bit and tube are secured within the stem of the pipe by a screw threading operation.

The tube 14 has its forward end rounded or tapered as at 18, and is provided with a plurality of longitudinally extending splits or the like 19, the purpose of which will be hereinafter described. The passage through the stem which is designated 20 is larger in diameter than the tube 14, and extends to the forward end of the lower section of the bowl, and passes through the bowl wall in the form of a relatively small opening designated 21. The forward end of this passage is tapered as at 22 to conform to the tapered end 18 of the tube 14, the purpose of which taper will be hereinafter described.

In carrying out the present invention, a passageway such as designated 24 in Figure 1 is bored from the bottom of the pipe bowl upwardly into the wall of said bowl and a plug member such as 25 is adapted to be inserted into this passageway 24. The upper end of the passageway 24 is reduced as at 26, and the plug 25 has a still further reduced portion 27 which is adapted to be received within the reduced portion 26 of the passage 24 to provide a space 28 around the reduced end of the plug. The space 28 has communication with the interior of the bowl 10 by means of a passageway such as 30 which may be formed by inserting a rotary circular tool 31 into the pipe bowl as shown in Figure 7, and cutting through the wall thereof with said tool at such a location in the wall of the pipe bowl that the passage formed by the tool will intersect the passage 24 at the upper end thereof or at the lower end of the reduced portion 26 thereof, all as illustrated in Figure 7.

The plug 25 has a passage 34 extending therethrough and said passage has communication at its upper end with the space 28 as best illustrated in Figure 4. Extending 106

through the plug 25 at substantially right angles to the passage 34, there is a passage 36 and this passage 36 is adapted to receive the tube 14 as best illustrated in Figures 1 and 4.

By reference to Figure 4 it will be noted that when the pipe is completely assembled, the slits 19 will have communication with the passage 34 through the plug 25 and it is by means of these slits 19, the passage 34, 10 the space 27, and the passageway 30 that communication is established between the bowl and the tube 14.

From the foregoing description, it will be apparent that saliva which enters the bit 12 and from whence it passes into the tube 14, 15 will be trapped in the forward end of the tube 14, and will not pass upwardly through the passage 34 and the space 27 to the interior of the bowl 10 during normal smoking of the pipe.

When it is desired to clean the bit and stem, it is only necessary to back off the bit slightly with respect to the stem 11, when the free end of the stem will be open and a pipe cleaner may be passed through the bit 12, the tube 14 and onwardly through the opening 21 in the bowl thus cleaning the tube and removing any deposits or sediment which may have collected therein. After the above cleaning operation has been carried out, the bit is again turned home and the tapered end of the tube 14 will engage the curved wall 22 heretofore mentioned and close the same together with the opening 21. This opening 21 however may not be entirely closed and in operation of the pipe a slight inflow of air at this point may result. The inflow of air however will not be sufficient to interfere with the perfect draft of the pipe, and will also have the added advantage of cooling the smoke.

When it is desired to clean the communicating passages between the bowl and the tube 14, the tube is entirely removed from the stem 11, or back out of the same sufficiently to permit of the end 18 thereof clearing the plug. The plug may then be removed, the passages cleaned and the plug likewise cleaned when it is again inserted into the passage 24 and the stem passed therethrough to the position illustrated in Figure 1.

For removing the plug 25, I provide a key 40 which is best illustrated in Figure 6, and 40 said key consists of a plug embracing portion 41 having hooked ends 42. These hooked ends are adapted to pass through longitudinally extending passages 43 in the plug 25 and into an annular channel 44, after 40 which the key is slightly turned so that its projecting ends 42 engage beneath the flange 45 formed by the annular channel 44, whereupon the plug may be freely or readily withdrawn from the passage 24 by the key 40.

From the foregoing it will be apparent

that the present invention provides a new and improved smoking pipe which will be sanitary, which may be readily cleaned, in which the saliva cannot enter the bowl and the contents thereof, and in which the exterior of the bowl is not disfigured by the peculiar arrangement of the parts within the pipe stem and bowl.

While the invention has been herein illustrated in a preferred form, it is to be understood that the invention is not to be limited to the specific construction shown, and that it may be practiced in other forms without departing from the spirit thereof.

Having thus described the invention, what is claimed as new, and what it is desired to secure by Letters Patent of the United States, is:

1. In a smoker's appliance, a body having a bowl and a stem, said body having a bore extending through the bowl and stem, the end portion of said bore within the bowl being reduced in diameter, a bit, a tubular member attached to said bit and positioned within said bore, one end portion of said tubular member being provided with a plurality of incisions extending lengthwise thereof and defining partly severed portions having tapering free ends for engaging the wall of the constricted portion of the bore. 95

2. In a smoker's appliance, a body having a bowl and a stem, said body having a bore extending through the bowl and stem, the end portion of said bore within the bowl being reduced in diameter, a bit, a tubular member attached to said bit and positioned within said bore, one end portion of said tubular member being provided with a plurality of incisions extending lengthwise thereof and defining partly severed portions having tapering free ends for engaging the wall of the constricted portion of the bore, and a plug carried by said body and having means cooperating with the bore to establish communication between the bowl and the interior of said tubular member. 105

In testimony whereof I affix my signature.

SALVATORE LAFRANCA.
